(57) CLAIM

The ornamental design for an in-line static mixer, as shown and described.

DESCRIPTION

FIG. 1 is a front, side perspective view of an in-line static mixer positioned with pipe portions and showing my new design;

FIG. 2 is a front perspective view thereof with the pipe portions removed for clarity;

FIG. 3 is a side elevation view thereof;

FIG. 4 is a front elevation view thereof;

FIG. 5 is a rear elevation view thereof; and,

FIG. 6 is a sectional view along the line 6—6 of FIG. 5 to better illustrate the positioning of an inner plate.

The dotted line showing of pipe portions in FIG. 1 is for illustrative purposes and form no part of the claimed invention.
